BODY EXERCISER

Francis Elmquist, Kansas City, Mo.

Application December 23, 1940, Serial No. 371,275

6 Claims. (Cl. 272—57)

This invention relates to body exerciser in the nature of a device particularly formed to receive the weight of the human body and act thereon as the user applies different parts of the body to the exerciser in such fashion as to break down fatty tissue and massage away surplus flesh.

One of the important aims of this invention is to provide a specially constructed exerciser upon which the user may rest a desired portion of his body as the exerciser is propelled along a supporting surface in a manner as to compress certain zones and force outwardly from a point of greatest pressure, the fleshy part of the body being treated.

A still further aim of this invention is the provision of an exerciser of the aforementioned character that comprises a barrel-like body upon which is mounted resilient annuli, the inherent character of which is such as to maintain the said body in a normal position where it will roll along a supporting surface with only the medial portion of greatest diameter engaging said surface.

A yet further object of the invention is to provide an exerciser for the human body which is of such shape and form as to strengthen the muscles of the user without injurious effects and within the minimum length of time.

Another aim of the invention is the provision of a body exerciser in the nature of a barrel-like body, which body has thereon suitable stops and a scale, both of which cooperate in indicating to the user the distance which the body will travel, which scale and stop are employed to predetermine the amount of travel, depending upon the portion of the body being treated.

This invention has for a still further object the provision of a body exerciser which includes a track to support the movable member and to indicate the distance of travel through which the barrel-like body moves when in use.

A large number of specific objects will appear during the course of the following specification, referring to the accompanying drawing wherein:

Fig. 1 is a top plan view of a body exerciser made in accordance with the present invention.

Fig. 2 is an end view of the same.

Fig. 3 is an enlarged detailed fragmentary sectional view taken on line III—III of Fig. 2.

Fig. 4 is a vertical longitudinal sectional view through a body exerciser made in accordance with a modified form of the invention and including a track.

Fig. 5 is a cross sectional view through the assembly shown in Fig. 4, taken on line V—V thereof; and

Fig. 6 is an enlarged fragmentary elevational view of a portion of the frame illustrating the movable stop and scale.

The preferred form and one modification of the invention is shown in the illustrated embodiment of the exerciser and the manner of producing the same will become apparent to one skilled in the art when it is understood that the body portion of the exerciser comprises a body 6, which is symmetrical and barrel-like in form so that the greatest diameter is on a transverse medial plane intermediate the ends. This area of greatest diameter is indicated by the numeral 8, and as the ends of body 6 are approached, the diameter thereof progressively decreases.

Ends or heads 10 are positioned to close body 6 so that it becomes a hollow member relatively light in weight and easy to manipulate.

A specially formed hoop 12 circumscribes body 6 adjacent to each end respectively thereof, and each hoop carries an annulus 14 which is molded or otherwise formed of resilient material such as rubber. The material from which each hoop 14 is formed, is preferably sponge rubber of medium resiliency so that as body 6 tips, the annuli will be compressed and tend to return the body to a normal position where its longitudinal axis is on a true horizontal plane. Thus, the muscles of the user are tensed and strengthened as balance is maintained and as the body of the user is engaged with a force greater at a given point than at any place around said point of engagement. Hoops 12 are U-shaped in transverse cross section and grip the inner marginal portions of the respective annuli 14 as illustrated in Fig. 3.

A ring-shaped scale 16 is mounted on body 6 adjacent to each resilient annulus 14 and indicia, such as illustrated at 18, is engraved or otherwise placed thereon so that the pointers 20 of the proximal stops 22 may cooperate therewith in indicating to the operator the distance which body 6 will roll during the exercising period.

There is a stop 22 slidably mounted upon each of the specially formed hoops 12. Each stop comprises a U-shaped yoke 24 which straddles the annulus 14 and frictionally engages the outturned legs of hoop 12. Grips 26 on yoke 24 may be employed by the operator when the stop is to be adjusted and pointer 20 may be merely a continuation or an inwardly directed portion of inner grip 26.

Yoke 24 has a radially extended bumper 28 secured therethrough through the medium of bolts or similar elements 30, and the outer end of bumper 28 is provided with angled faces 32 so that when body 6 is rolled to the position shown in dotted lines (Fig. 2) from the position shown in full lines, bumper 28 will strike the supporting surface and preclude further travel.

In operating the body exerciser, shown in Figs. 1 to 3, the distance of travel of body 6 should be great enough to contact all portions of the body being treated. As an example, when strengthening the abdominal muscles, the distance of travel of body 6 should be approximately fifteen inches. When body 6 is in the set position, the scales 16 should be arranged so that zero is uppermost or on the highest portion of the body 6. Pointers 20 are then moved to above the figure fifteen on scale 16 by sliding yoke 24 along hoop 12. Rotation in one direction will then be limited to the desired amount and there will be no danger of the operator gliding forward over the top of body 6, a distance greater than desired or recommended.

The form of body exerciser shown in Figs. 4 to 6 inclusive, comprises a body 100 similar to that employed in constructing the exerciser shown in Fig. 1, which is likewise symmetrical and barrel-like in form to present the greatest diameter thereof on a transverse medial plane intermediate the ends.

A specially formed saddle 102 provided with longitudinal ridges or corrugations 104, is strapped or otherwise secured to the barrel as at 106. The corrugations or ridges 104 include a core of resilient material 108 sheathed in the fabric from which saddle 102 is constructed. When exceptionally fleshy portions of the body are to be treated by work on the exerciser, this saddle 102 may be employed.

Body 100 rolls upon a track generally designated by the numeral 110 and which includes opposed strips 112 that rest directly upon the supporting surface, such as the floor and along which extend flanges 114 a distance apart slightly greater than the overall length of body 100. Protecting strips of sheet metal 116 lie along the inner and upper edges of flanges 114 and upon these strips 116 is engraved or otherwise marked, a scale 118 to indicate the distance of travel of body 100. Any suitable marker or pointer on body 100 will indicate the starting point.

Stops 120 at each end of track 110 and at each side thereof, have an arcuate face 122 conforming to the radius of the outer face of body 100. These stops are carried by the frame and one set thereof is longitudinally adjustable through the employment of slots 124 that receive bolts 126. Thumb nuts 128 allow releasably securing stops 120 in the desired position along the track.

It is desired to start the body from one end of track 110 where it rests against stops 120 at said end and to limit the rolling movement by affixing the adjustable stops at a point along track 110 selected by the operator. Mark 130 may be brought into register with indicia 132 on scale 118 to reveal the distance the body moves.

The exerciser may be used by the operator in many ways, for example, the back, sides and abdomen may be strengthened and reduced. Other exercises well-known to one skilled in the art, are also possible when employing this specially formed body exerciser.

Having thus described the invention, what is

claimed as new and desired to be secured by Letters Patent is:

1. A body exerciser of the character described comprising a barrel-like symmetrical body having its greatest diameter on the medial transverse plane and progressively decreasing in diameter as the ends are approached; an annulus circumscribing the body at each end respectively thereof, the diameter of the annuli being slightly less than the greatest diameter of the body at the center thereof; a hoop-shaped scale mounted on the body adjacent to one of the annuli; and a stop carried by the body in operative relation with the scale.
2. A body exerciser of the character described comprising a barrel-like symmetrical body having its greatest diameter on the medial transverse plane and progressively decreasing in diameter as the ends are approached; an annulus circumscribing the body at each end respectively thereof, the diameter of the annuli being slightly less than the greatest diameter of the body at the center thereof; a scale mounted on the body adjacent to one of the annuli; and a stop slidably supported by the last mentioned annuli in operative relation with the scale.
3. A body exerciser of the character described comprising a barrel-like symmetrical body having its greatest diameter on the medial transverse plane and progressively decreasing in diameter as the ends are approached; an annulus circumscribing the body at each end respectively thereof, the diameter of the annuli being slightly less than the greatest diameter of the body at the center thereof; a scale, having indicia thereon, mounted on the body adjacent to each of said annuli; and a stop slidably supported by each annulus in operative relation with the proximal respective scale.
4. A body exerciser of the character described comprising a barrel-like symmetrical body having its greatest diameter on the medial transverse plane and progressively decreasing in diameter as the ends are approached; a hoop circumscribing the body at each end respectively thereof; an annulus of resilient rubber or the like around each of said hoops, the outside diameter of the annuli being slightly less than the outside diameter of the body at the center thereof; a scale, having indicia thereon, mounted on the body adjacent to each of said annuli and extending around the body in close proximity to the annuli; and a stop slidably supported by each hoop, said stop having a pointer thereon to cooperate with the scale in the manner specified.
5. A body exerciser of the character described comprising a barrel-like symmetrical body having the greatest diameter on the medial transverse plane and progressively decreasing in diameter as the ends are approached; an annulus of resilient material circumscribing the body at each end respectively thereof; means formed of relatively stiff material for holding each annulus in place; and a stop mounted on said means, said stop projecting radially outwardly from the body beyond the annuli of resilient material.
6. A body exerciser as described in claim 5 wherein the outside diameter of the annuli is slightly less than the greatest diameter of the body at the center thereof and wherein the resiliency of the annuli is sufficient to cause a rebound when the body is longitudinally tipped to compress one of the annuli.
